KITE

Clyde H. Gossett, Van Nuys, Calif.

Application August 3, 1959, Serial No. 57,047

Term of patent 14 years

(Cl. D34—15)

Fig. 1 is a perspective view of a kite embodying my new design;

Fig. 2 is an enlarged side view of the kite;

Fig. 3 is a bottom view taken on line 3—3 of Fig. 2;

Fig. 4 is a rear view of the kite taken on line 4—4 of Fig. 2; and

Fig. 5 is a front view of the kite.

I claim:

The ornamental design for a kite, as shown.
